UNITED STATES PATENT OFFICE

MAX SCHNEIDER, OF DENVER, COLORADO, ASSIGNOR TO THE EGRY REGISTER COMPANY, OF DAYTON, OHIO, A CORPORATION OF OHIO

AUTOGRAPHIC REGISTER

Application filed December 13, 1928. Serial No. 325,829.

My invention relates to autographic registers.

It is the object of my invention to provide an autographic register in which a plurality of sheets may be maintained in alignment during the writing operation, positively ejected after the writing operation and realigned prior to a new operation. It is a further object of my invention to hold such realigned sheets after they have been realigned and during the writing operation.

It is an additional object of my invention to provide means for realigning the paper sheets one over the other and with respect to the writing opening without the use of a large number of perforations in the paper with the accompanying disadvantages and expense. It is a further object to be able to effect this realignment by using the same holes in the paper sheets which are afterwards used for mounting the slips in the usual sales slip binders, in which such sheets are preserved in loose leaf form in loose leaf books.

It is an additional object of my invention to provide means of automatically and synchronously adjusting the paper ejecting means and the paper aligning means and the holding of the paper so that the paper aligning means will be inoperative while the paper is being fed and the paper feeding means will be inoperative while the paper is being realigned; and upon the realignment the paper feeding means will again clamp the paper and put it in writing position.

It is an additional object of my invention to provide means for threading the sheets and maintaining them in a separated condition one from the other so that they may move one over the other freely during the realigning process, as such sheets have a tendency unless positively separated to cling to each other, due to the static electricity resident in the sheets which is maintained due to the frictional engagement of the sheets one with the other.

It is a further object of my invention to provide a simple means for ejecting the sheets and realigning them through the operation of one hand of the operator with a single

stroke of the operating crank. It is also my object to provide a releasing mechanism which can be worked by the fingers of the operator of the same hand which works the crank.

It is an additional object of my invention to provide a register of the above character which is self-contained, in which the operating mechanism can be locked so that it cannot be tampered with and in which there shall be the minimum of parts.

It is a further object of my invention to provide a register in which the threading mechanism and paper realigning mechanism may all be carried on the writing table, which facilitates the assembly of the structure, its removal from the register, and simplicity of operation. It is an additional object to provide all of the operating mechanism on the register frame, which will operate the mechanism carried by the writing table when the latter is placed in position, with the result that the operating mechanism is carried upon the relatively heavy, rigid frame which will insure accuracy of result. It is thus possible to assemble the two units separately and to detach them from one another without disturbing either mechanism, which greatly facilitates adjustments and repairs.

Referring to the drawings:

Figure 1 is a side elevation from the crank side of the register with a portion of the side of the register broken away to show some of the interior mechanism.

Figure 2 is a section through the register just inside of one of the walls of the register.

Figure 3 is a side elevation of the mechanism for realigning the paper in a position just prior to moving forward to engage with the paper.

Figure 4 is a similar view just at the end of the realigning stroke.

Figure 5 is a similar view just at the beginning of the realigning stroke.

Figure 6 is a bottom plan view of the writing table, showing the paper aligning mechanism.

Figure 7 is a top plan view of the paper threading mechanism and the aligning pins.

Figure 8 is a section on the line 8—8 of Figure 5.

In the drawings, 1 is the base of a register of conventional form which has the usual side walls 2, to which at the front of the register is pivoted at 3 a swinging door 4 that is locked at the top by the lock 5. There is a rear wall 6 and on top of the walls 2 at the rear of the register as at 7 there is pivoted a writing cover 8, having a writing opening 9, and a forwardly extending housing 10 for the upper feed roll. The forward end of this writing cover has projected lips 11, which rest upon the top of the side walls 2 and are engaged at that point by corresponding overlapping lips 12 of a sliding plate 13, which is locked in position by the end of the swinging front door 4.

In the register on transverse spindles 14, 15 and 16 are located the usual rolls of paper 17, which have printed thereon a plurality of forms in succession of the usual character and have punched therein between said forms a relatively large perforation about a fourth of the way from each margin. It will be noted that it is preferable to use two relatively large perforations which are spaced inwardly an appreciable distance from the sides of the form. This permits of the use of large pins with broad bearing surfaces, so that the paper will not be easily torn. It also permits of using the same holes for the binder posts when the ejected tickets are bound in loose leaf books.

These rolls of paper have their sheets conveyed upwardly over the end of the writing table 18. The lowermost sheet travels over the table directly in contact with it. The next sheet is separated from the first sheet by the plate 19, which is located above the writing table and spaced therefrom approximately the depth of a single sheet of paper. The next succeeding sheet is spaced by the spacing plate 20 and is kept in position by a plate 21 which is spaced from the plate 20 approximately the thickness of a sheet. These spaced plates have elongated apertures 22 so as to accommodate the fore and aft movement of the pins 23, which work in these slots 22 and project through them upon occasion for the rearward movement of the paper sheets. As will be seen in Figures 3, 4, 5 and 7 these plates 19, 20 and 21 are staggered so that threading of the sheets between them is facilitated. The paper sheets are conveyed forwardly over the writing table beneath the writing opening 9. The usual carbon interleaves are threaded between the respective sheets to insure carbon copies. The forward free ends of the sheets pass between the knurled paper ejecting roller 24 which is the lower roller, and 25 which is the upper roller. These rollers are driven in unison by the gears 26 and 27, which are mounted on their ends. The lower roller 24 is perma-

nently journaled in the side walls of the register, while the upper roller has the ends of its shaft carried in a slot 28, so that it can move up and down freely, but is resisted in this movement by a helical spring 29, which bears on either end of the roller shaft 30 to force the upper roller into engagement with the paper sheets and the lower roller. As will be hereinafter described the separating fingers 31 may be forced between such rollers to separate them, while the paper is being realigned. This separation may either be automatic with the turning of the handle 32, or normally effected at any desired time through the agency of the thumb piece 33 which is carried on the outside of one wall of the register.

The handle 32 is mounted on a shaft 34, which is journaled in the side walls of the register. On one end of the shaft inside of the register wall is carried a gear 35, which meshes with an intermediate pinion 36 carried on the inside of said side wall, which pinion in turn meshes with the gear 26 to drive the paper feed rolls. A locking pawl 37 which is pivoted on the inside of the side wall as at 38 has a locking tooth 39, which engages with the teeth of the gear 35 to prevent the backward movement of this train of gears.

The forward and free end of the crank 32 rests upon a rocking latch. The head of this latch is designated 40 and the operating finger piece is designated 41. It is pivoted on the outside of the side wall of the register on the stub shaft 42. It is so arranged that it will return to its locking position under the influence of a spring 43.

It is prevented from moving under the influence of this spring in one direction by a stop 44, which engages with a shoulder 45 on the locking finger. This stop is carried by the outside of the register wall.

When the finger of the operator's hand, which is being used to operate the crank 32, is used to pull the locking finger 41 backwardly the crank 32 is released for its downward movement. As the crank goes downwardly the forward rolls are actuated through the train of gears and the paper is ejected.

Coincident with this movement, as will be seen from a description of Figure 3 and subsequent figures, the pins 23 are allowed to drop due to the fact that when this locking finger is pulled backwardly and by reason of this backward movement, the sleeve 46 which is mounted on the stub shaft 42 moves a lever 47 on the inner end of 46. This lever in turn actuates the connecting rod 48 and rocks a lever 49 pivoted at 50, the upper end of which is equipped with a transverse pin 51, which serves to lift the latching lever 52 for the disengagement of the locking pin 53 from the notch 54 in the latching lever 52. The spring 55

55 is so arranged that it constantly tends to keep the latching lever 52 in engagement with the pin 51, either by having its cam nose 56 in engagement therewith, or the notch 54 in engagement with it. As soon as the pin 51 is disengaged from the notch 54, this permits the shaft 57 to rock. This shaft is rocked under the influence of the spring 58, which is connected to the shaft at one end and to the 10 sliding plate 59 at the other, as at 60. The shaft is freely journaled in the downwardly extending arms 61, which are carried by the sliding plate 59. On the end of the shaft 57 is a crank 62 which carries the transverse locking pin 53 heretofore described. Also carried on this shaft 57 are the pin arms 63 which have pivotally mounted in their free ends, as at 64 between the jaws 65, the pins 23. These pins reciprocate when the shaft 57 20 rocks through the plate 59 in apertures provided for that purpose. Accordingly, when the pin 53 was released from the notch 54 under the influence of the spring 58 the shaft 57 rocked forwardly and withdrew the pins 23 downwardly out of engagement with the paper. The plate 59 remains stationary, however, at this stage due to the fact that the plate locking lever 66, which is pivoted on the bottom of the writing table at 67 has a head 68 which engages with the forward edge of the plate 59 to prevent its forward movement under the influence of the spring 69, one end of which is attached at 70 to the plate 59 and the other end at 71 to one of the guides 72, which are permanently fastened upon the bottom of the writing table. A companion guide 73 is provided, spaced from the guide 72. These guides embrace the sliding plate 74 to guide it in its fore and aft movement 40 on the bottom of the writing table. This sliding plate 74 moves with the plate 59 and forms a T-shaped structure. The locking lever 66 is mounted in its locking position by the spring 75, the free end of which at 76 45 bears against the bottom of the writing table and the other end of which is attached at 77 to the lever itself.

Mounted on the shaft 57 is a pair of jaws 78, between the free ends of which is mounted one end of the shaft 79, which carries the block 80. These jaws 78 are provided with a stop 81 for engaging with the lower surface of the slides 74 to limit the forward movement of the shaft 57 and the rod 79 under the influence of the spring 58.

The forward end of this shaft 79 is provided with a vertical support 82, which is slidably mounted upon the plate 83, which is carried upon the lower surface of the slide 60 74. This plate has slots 84, which permit its sliding relative to the guide studs 85 carried on the under side of the sliding plate 74.

The depending end of this vertical support 82 carries a forwardly extending arm 86 and 65 on the end of that arm a cam 87 which tapers

downwardly. This cam engages with a second cam which is arranged as follows. This cam is mounted on the crankshaft 34. It consists of a relatively flat surface 88 terminating in a rounded head 89. This flat surface is projected at substantially right angles of the shaft 34. On the other side of this cam the cam is recessed to form a second cam surface 90, which projects outwardly to form a relatively thick cam portion 91 as distinguished from the cam finger 92.

When the parts are as shown in Figure 4, the handle will be in its at-rest position and the engagement of the cam 87 with the end 89 of the cam finger 92 will maintain the pins 80 in engagement with the paper. The first movement of the handle will move the finger 92 upwardly and forwardly with the result that the parts will assume the position shown in Figure 3 with the cam 87 resting against 85 the cam surface 90 with the pins withdrawn from the paper. The continued forward movement of the cam on the shaft 34 will result in the cam 90 being disengaged from the cam 87 and under the influence of the spring 69 the pins, plate, rod 79 and cam 87 will move forwardly to the position shown in Figure 5 for reengagement with the paper. This reengagement does not take place until the handle is about three-fourths of the distance 95 through its revolution and at that time the paper tickets have been fully ejected. As the handle continues to operate the cam on the shaft 34 will be elevated so that its surface 88 will engage with the cam 87 to thrust 100 it backwardly with the result that the pins 23 are thrust upwardly through the paper, as the holes in the paper will at this time be directly over such pins and the pins will align the sheets one over the other. The continued 105 movement of the crank shaft 34 will cause the rearward movement bodily of the pins, which are now elevated, and of the sliding plates 59 and 74 against the resistance of the spring 69. This will have the result of drawing 110 the paper sheets backwardly to writing position. Such withdrawal can be accomplished because the sheets have been released from the grip of the feed rollers 24 and 25 just prior to the insertion of the pins in the paper. 115 When the end of the stroke is reached just prior to the handle coming to rest by its engagement with the locking finger 40, the locking lever 66 will lock the plate 59 against forward movement and the pin 53 will drop 120 in the slot 54 of the latching lever 52.

In order to insure the positive unlatching of the locking lever 66, the forward free end is adapted to ride on a cam 93, which is cut away at 94 to permit the lever to drop down 125 in locking position. When the handle starts to rotate, the cam 93 elevates the free end of the plate locking lever 66 against the resistance of the spring 75.

Turning to the operation of the rolls to ren- 130

der them inoperative when the feeding operation is completed, it will be observed that on the shaft 34 there is mounted a third cam 95. This cam engages with the end of a lever 96 which is mounted upon a cross shaft 97, which is pivotally mounted in the walls of the register. Either end of this shaft carries a crank 98 on the free end of which is pivotally mounted at 99 the spreading finger 31. On either side of the register there are mounted the same mechanisms as illustrated in Figure 2 so that the spreading nose or cam 100 will spread the rolls evenly on either side. This spreading may be effected manually directly by actuating the thumb piece 33, which is mounted on the outside of the register on the shaft 97. This spreading is resisted by the helical springs 29.

In order to understand the details of this invention, the following statement of the movements and operations which take place in my register will be of assistance. Assuming the crank to be in its normal at-rest position at the end of a stroke, resting upon the 25 rocking fingers on the side of the register, the feed rolls will be clamped upon the paper and the aligning pins will be in the holes in the paper at the opposite ends of the tickets. Thus, the paper is held both at its front end 30 and at its rear end.

The first step is to unlatch the handle by pulling the trigger backwardly, upon which the handle rests and which prevents its forward movement. This not only releases the 35 handle so that it can make its revolution, but it also permits the pins to drop out of engagement with the paper sheets. These paper sheets are separated by spaced metal strips at the rear of the tickets in order to insure 40 the free moving of one sheet over the other.

The handle then starts to turn and during the first portion of its stroke it moves far enough to permit the pins to move forwardly. During this movement the feed rolls 45 which are in engagement with the paper have been feeding the paper forwardly and continue to do so until about three-fourths of the stroke of the handle has been accomplished. At this point the feed rolls are separated by the continued movement of the 50 handle and simultaneously the aligning pins are elevated and engaged with the holes at the rear of the strips which have not yet been written upon. The remaining fourth of the 55 stroke is occupied by a forward movement of the handle and a rearward movement of the pins and plate beneath the writing table with the several sheets which are permitted to be moved back to realigned position be-

60 cause their forward ends have been released of the engagement of the feeding rolls. Upon the handle coming to rest the feed rolls will reengage the paper and as the pins are still in engagement with the paper, the sheets will 65 be held in position for the writing operation.

It will thus be seen that any displacement of the sheets due to their forward movement by the feeding rolls will be corrected by the sheets being drawn back by the pins being thrust through the holes in the paper, which are located in a predetermined position and serve to realign the sheets. This withdrawal of the paper to writing position also positions the sheets directly beneath the writing opening. 70 75

I desire to comprehend within my invention such modifications as may be necessary to adapt it to varying conditions.

Having thus fully described my invention, what I claim as new and desire to secure by Letters Patent, is:

1. In an autographic register having a plurality of sheets, the combination with paper feeding means, an operating crank to actuate the paper feeding means, and means to render inoperative said feeding means at a predetermined time, of paper aligning pins remote from said feeding means adapted to enter perforations in the sheets substantially at that time, and means actuated by the operating crank to effect the entrance of the aligning pins into the paper perforations, to move the aligning pins longitudinally to effect the alignment of the paper and to withdraw the aligning means from the paper at right angles thereto, all these actions resulting from the turning of the operating crank, and means for simultaneously rendering the feeding means inoperative while the aligning operation is taking place. 90 95 100

2. In an autographic register having a plurality of sheets, means to engage with the sheets to eject them, means to be inserted in spaced apertures in said sheets to align them, means to move said aligning means backwardly to draw the aligned sheets back into writing position, means for simultaneously rendering the feeding means inoperative while the aligning operation is taking place, said aligning means consisting of pins projected into said sheets and withdrawn therefrom substantially at right angles, a common actuating means for paper feeding and paper aligning, and means consisting of a latch adapted to limit the movement of said common actuating means and so connected to said pins that when it is unlatched it will cause the pins to be withdrawn from engagement with the paper. 110 115 120

3. In an autographic register having a plurality of sheets, means to engage with the sheets to eject them, means to be inserted in spaced apertures in said sheets to align them, means to move said aligning means backwardly to draw the aligned sheets into writing position, means for simultaneously rendering the feeding means inoperative while the aligning operation is taking place, said aligning means consisting of pins projected into said sheets and withdrawn therefrom 125 130

- substantially at right angles, a common actuating means for the paper feeding and paper aligning, means consisting of a latch adapted to limit the movement of said common actuating means and so connected to said pins that when it is unlatched it will cause the pins to be withdrawn from engagement with the paper, and means for moving said pins forwardly out of engagement with the paper controlled by said common actuating means to place the pins in position for reengagement with the paper at the moment said common actuating means renders the feeding means inoperative and simultaneously reinserts the pins in the paper and withdraws the pins and paper to writing position, and means for reengaging the paper feeding means with the paper to hold it during the writing operation.
4. In an autographic register having a plurality of sheets, means to engage with the sheets to eject them, means to be inserted in spaced apertures in said sheets to align them, means to move said aligning means backwardly to draw the aligned sheets into writing position, means for simultaneously rendering the feeding means inoperative while the aligning operation is taking place, said aligning means consisting of pins projected into said sheets and withdrawn therefrom substantially at right angles, a common actuating means for the paper feeding and paper aligning, means consisting of a latch adapted to limit the movement of said common actuating means and so connected to said pins that when it is unlatched it will cause the pins to be withdrawn from engagement with the paper, means for moving said pins forwardly out of engagement with the paper controlled by said common actuating means to place the pins in position for reengagement with the paper at the moment said common actuating means renders the feeding means inoperative and simultaneously reinserts the pins in the paper and withdraws the pins and paper to writing position, and means for reengaging the paper feeding means with the paper to hold it during the writing operation, said common actuating means being arranged to effect the operation of such mechanism by a single continuous movement of such common operating means.
5. In an autographic register having a plurality of sheets, means to actuate said sheets, means to render inoperative said actuating means, and sheet aligning means having pins thereon to engage said sheets to align them, means to draw back said sheets in aligned position to writing position, means to reengage said sheets during the writing operation for feeding new sheets, and plates having holes therein to receive the aligning means to separate each of the sheets of paper so that they can freely move one over the other during the realigning operation.
6. In an autographic register having a plurality of sheets, means to actuate said sheets, means to render inoperative said actuating means, sheet aligning means having pins thereon to engage said sheets to align them, and means to draw back said sheets in aligned position to writing position, means to reengage said sheets during the writing operation for feeding new sheets, means to withdraw the aligning means just prior to ejecting the sheets which have been written upon, and plates having holes therein to receive said aligning means to separate each of the sheets of paper so that they can freely move one over the other during the realigning operation.
7. In an autographic register having a plurality of sheets, means to actuate said sheets, means to render inoperative said actuating means, sheet aligning means having pins thereon to engage said sheets to align them, and means to draw back said sheets in aligned position to writing position, means to reengage said sheets during the writing operation for feeding new sheets, means to withdraw the aligning means just prior to ejecting the sheets which have been written upon, means for restoring the aligning means to a position to reengage said sheets, and plates having holes therein to receive said aligning means to separate each of the sheets of paper so that they can freely move one over the other during the realigning operation.
8. In an autographic register having a plurality of sheets, means to actuate said sheets, means to render inoperative said actuating means, means remote from said means to actuate said sheets to engage said sheets to align them, and means to draw said sheets in aligned position to writing position, means to reengage said sheets during the writing operation for feeding new sheets, means to withdraw the aligning means just prior to ejecting the sheets which have been written upon, means for restoring the aligning means to a position to reengage said sheets, means to restore the means for withdrawing the sheets from the writing position to a position where a new operation may take place of withdrawing the sheets, and plates to separate each of the sheets of paper so that they can freely move one over the other during the realigning operation.
9. In an autographic register having a plurality of sheets, means to engage with the sheets to eject them, means to be inserted in spaced apertures in said sheets to align them, means to move said aligning means backwardly to draw the aligned sheets into writing position, means for simultaneously rendering the feeding means inoperative while the aligning operation is taking place, said aligning means consisting of pins projected into said sheets and withdrawn therefrom substantially at right angles, and means to separate each of the sheets of paper so

that they can freely move one over the other during the realigning operation.

10. In an autographic register having a plurality of sheets of paper with spaced apertures in said paper, means for frictionally engaging said paper to eject it, means to separate said sheets of paper, means adjacent to the separating means for engaging in the holes in said paper, and means for simultaneously releasing the ejecting means in its engagement with the paper, said hole engaging means consisting of pins thrust through said paper and separating means, and means for moving said pins backwardly with the paper through the separator, means for restoring the ejecting means in engagement with the paper while the pins are in the paper, and means of withdrawing said pins abruptly from the paper.
15. 11. In an autographic register having a plurality of sheets of paper with spaced apertures in said paper, means for frictionally engaging said paper to eject it, means to separate said sheets of paper, means adjacent to the separating means for engaging in the holes in said paper, and means for simultaneously releasing the ejecting means in its engagement with the paper, said hole engaging means consisting of pins thrust through said paper and separating means, and means for moving said pins backwardly with the paper through the separator, means for restoring the ejecting means in engagement with the paper while the pins are in the paper, and means of withdrawing said pins abruptly from the paper, said pins being thrust into and removed from said paper at substantially right angles thereto.
20. 12. In an autographic register having a plurality of sheets of paper with spaced apertures in said paper, means for frictionally engaging said paper to eject it, means to separate said sheets of paper, means adjacent to the separating means for engaging in the holes in said paper, and means for simultaneously releasing the ejecting means in its engagement with the paper, said hole engaging means consisting of pins thrust through said paper and separating means, and means for moving said pins backwardly with the paper through the separator, means for restoring the ejecting means in engagement with the paper while the pins are in the paper, and means of withdrawing said pins abruptly from the paper, said holes being relatively large and spaced from one another a greater distance than from the margin of the paper and relatively large pins closely fitting in said holes.
25. 13. In an autographic register having a plurality of sheets of paper and holes arranged in series transversely of the paper at intervals with a predetermined relation to forms printed on said paper, said holes being back from the margin of the sheets a substan-

tial distance, means for frictionally engaging and ejecting the sheets of paper, means for separating the sheets of paper so that they will freely slide over one another, means for rendering the ejecting means inoperative and simultaneously inserting pins in said apertures, means for moving said pins with the sheets backwardly to a new writing position in realigned condition, means for reengaging the paper ejecting means with the paper, and means for withdrawing the pins from the paper upon the starting of a new cycle of ejection.

30. 14. In an autographic register having a plurality of sheets of paper and holes arranged in series transversely of the paper at intervals with a predetermined relation to forms printed on said paper, said holes being back from the margin of the sheets a substantial distance, means for frictionally engaging and ejecting the sheets of paper, means for separating the sheets of paper so that they will freely slide over one another, means for rendering the ejecting means inoperative and simultaneously inserting pins in said apertures, means for moving said pins with the sheets backwardly to a new writing position in realigned condition, means for reengaging the paper ejecting means with the paper, and means for withdrawing the pins from the paper upon the starting of a new cycle of ejection, said several means being actuated from a common actuating means which effects the cycle of operations at a single continuous stroke.

35. 15. In an autographic register having a plurality of sheets with spaced groups of perforations, a writing table, an operating handle and a shaft, friction rollers adapted to engage with the paper, a cam on said shaft, spreading fingers adapted to be actuated by said cam to spread said rollers at a predetermined point, means to rotate said rollers from said operating shaft, paper engaging pins carried beneath said writing table and adapted to project therethrough, a cam on said operating shaft adapted to control the fore and aft movement of said pins and adapted to control the entrance and exit of said pins in the paper sheets, means to lock said pins in paper engaging position, means to lock said pins in their rearmost position, a cam on the operating shaft to control the last mentioned operating means, and means associated with the operating shaft and its handle for unlocking the pin locking means.

40. 16. In an autographic register having a plurality of sheets with spaced groups of perforations, a writing table, an operating handle and a shaft, friction rollers adapted to engage with the paper, a cam on said shaft, spreading fingers adapted to be actuated by said cam to spread said rollers at a predetermined point, means to rotate said rollers from said operating shaft, paper en-

gaging pins carried beneath said writing table and adapted to project therethrough, a cam on said operating shaft adapted to control the fore and aft movement of said pins 5 and adapted to control the entrance and exit of said pins in the paper sheets, means to lock said pins in paper engaging position, means to lock said pins in their rear-most position, a cam on the operating shaft 10 to control the last mentioned operating means, means associated with the operating shaft and its handle for unlocking the pin locking means, and yielding means to cause said cams to be followed and the pins positioned for reengagement with the paper. 15

17. In an autographic register having a plurality of sheets, a writing table over which a plurality of sheets of paper may pass, means to separate said sheets, means to feed 20 said sheets, a slide carried beneath said writing plate, reciprocatory pins adapted to be projected through said writing plate and travel in slots therein, means for restoring the slide to initial paper engaging position, 25 means for restoring the pins to initial paper engaging position, a transverse rod and arms mounted thereon carried by said slide adapted to project the pins through the slots into the paper, a crank on said shaft adapted to 30 engage with the slide to limit its movement in one direction, a rod connected to said crank and a cam on the end of said rod, an operating shaft connected to an operating handle, a cam on said operating shaft engaging with 35 the cam on said rod, whereby as the handle is actuated the pins will be thrust into holes in the paper and then move backwardly with the paper.

18. In an autographic register having a 40 plurality of sheets, a writing table over which a plurality of sheets of paper may pass, means to separate said sheets, means to feed said sheets, a slide carried beneath said writing plate, reciprocatory pins adapted to be projected through said writing plate and travel in slots therein, means for restoring the slide to initial paper engaging position, means for restoring the pins to initial paper engaging position, a transverse rod and arms 45 mounted thereon carried by said slide adapted to project the pins through the slots into the paper, a crank on said shaft adapted to engage with the slide to limit its movement in one direction, a rod connected to said crank 50 and a cam on the end of said rod, an operating shaft connected to an operating handle, a cam on said operating shaft engaging with the cam on said rod whereby as the handle is actuated the pins will be thrust into holes in 55 the paper and then move backwardly with the paper, a latching lever pivotally supported beneath said writing table having a notch adapted to engage with the pin on the shaft carrying the paper engaging pins, and 60 means for unlatching said latching lever 65

from said pin, whereby the pins are withdrawn from the paper.

19. In an autographic register having a plurality of sheets, a writing table over which a plurality of sheets of paper may pass, means to separate said sheets, a slide carried beneath said writing plate, reciprocatory pins adapted to be projected through said writing plate and travel in slots therein, means for restoring 70 the slide to initial paper engaging position, means for restoring the pins to initial paper engaging position, a transverse rod and arms mounted thereon carried by said slide adapted to project the pins through the slots into 75 the paper, a crank on said shaft adapted to engage with the slide to limit its movement in one direction, a rod connected to said crank and a cam on the end of said rod, an operating shaft connected to an operating handle, a cam on said operating shaft engaging with 80 the cam on said rod, whereby as the handle is actuated the pins will be thrust into holes in the paper and then move backwardly with the paper, a latching lever pivotally supported beneath said writing table having a notch adapted to engage with the pin on the shaft carrying the paper engaging pins, means for unlatching said latching lever from said pin, whereby the pins are 85 withdrawn from the paper, and a second cam controlling the slide locking lever, a slide locking lever, said second cam being so arranged to unlock the slide after the pins have been withdrawn from the paper, and means 90 for restoring said slide and pins to their paper engaging position.

20. In an autographic register having a plurality of sheets of paper, an operating shaft and handle, a movable stop for the 105 handle, pins adapted to project into the paper at substantially right angles thereto, means to normally withdraw said pins from engagement with the paper, said stop being arranged when it is actuated to free the handle to unlock the pin withdrawing means, means for moving said pins bodily to an engaging position with the paper longitudinally of the paper, means carried on the operating shaft for controlling the locking 110 and unlocking of this pin moving means, and means on the operating shaft for thrusting said pins into the paper and moving said pins back to the starting position where they were withdrawn from the paper, and means 115 for ejecting the paper operated by said operating shaft, and means for rendering said ejecting means inoperative while the pins and pin moving means are moving backwardly with the paper.

21. In an autographic register having a plurality of sheets of paper, an operating shaft and handle, a movable stop for the 120 handle, pins adapted to project into the paper at substantially right angles thereto, 130

means to normally withdraw said pins from engagement with the paper, said stop being arranged when it is actuated to free the handle to unlock the pin withdrawing means, 5 means for moving said pins bodily to an engaging position with the paper longitudinally of the paper, means carried on the operating shaft for controlling the locking and unlocking of this pin moving means, means on the operating shaft for thrusting said pins 10 into the paper and moving said pins back to the starting position where they were withdrawn from the paper, means for ejecting the paper operated by said operating shaft, 15 means for rendering said ejecting means inoperative while the pins and pin moving means are moving backwardly with the paper, and yielding means to restore said pins and pin moving means to a position to 20 readily reengage the paper.

22. In an autographic register having a plurality of sheets of paper, and having a frame and a writing table, slots at the rear of said writing table, feed rollers at the forward 25 end of said writing table, a slide on the bottom of said writing table, arms on said slide, a transverse shaft carried by said slide arms, other arms mounted on said shaft, pins pivotally mounted on the ends of said last mentioned arms adapted to be projected through the slots in the table, a lever on said shaft adapted to be limited by the slide as to its movement in one direction, yielding means to maintain the pins below the writing table, a 30 rod connected to the said lever, the free end of which is slidably supported on the slide, a cam carried on the end of the rod, a cam mounted on an operating shaft in the register connected to an operating handle, an operating shaft and handle, the cam being adapted to control the withdrawal of the pins, their forward movement, their reinsertion in the paper, and their return movement, a latch to 35 lock said pins in engagement with the paper at the end of the return movement, a second cam on the operating shaft adapted to unlock the slide to permit its forward movement and a locking means controlled thereby to lock the slide in its rearmost position, and yielding means to move said slide to its forward position, means connected to the operating shaft for controlling the operation of the paper ejecting means, and means to separate the sheets of paper on the writing table.

24. In an autographic register having a plurality of sheets of paper with spaced perforations therein, means at one end of said register to engage and eject said sheets, means at the other end of said register to engage said sheets in said perforations to align them, common means for actuating both of said means, and means to lock the last said means and to hold said means to engage and align said sheets in engagement with said sheets.

25. In an autographic register having a plurality of sheets, means for actuating said sheets, means to render said actuating means inoperative, perforated plates to separate said sheets so that they can freely move over one another, and means to engage and align said sheets, said means including pins passing through the said perforated plates.

26. In an autographic register having a plurality of sheets with spaced perforations therein, means at one end of said register for actuating said sheets, means to render said actuating means inoperative, perforated plates at the other end of said register to separate said sheets so that they can freely move over one another, and means passing through the perforations in said sheets and plates to align said sheets.

27. In an autographic register having a plurality of sheets with spaced perforations therein, means for actuating said sheets, means to render said actuating means inoperative, plates with elongated perforations therein to separate said sheets so that they can freely move over one another, and longitudinally and vertically movable means adapted to pass through said perforations for aligning said sheets.

28. In an autographic register having a plurality of sheets with perforations therein, plates with elongated perforations therein to

separate said sheets so that they can freely move over one another, and vertically and longitudinally movable means adapted to pass through said perforations for aligning said sheets.

5 29. In an autographic register, feed means for feeding apertured strips, an aligning pin, means for projecting said pin into the strip apertures, a crank for operating the feed means, a releasable stop for the crank, a rod connected to said stop, and means actuated upon movement of said rod to withdraw the pin from the paper apertures.

10 30. An autographic register including a casing adapted to house apertured record strips, a writing table in the casing, rollers for feeding the strips across the table, aligning pins, means to render the feed rollers inoperative to feed the strips during a portion 20 of a cycle of operations, and means to elevate said pins to engage in the strip apertures and to move the pins rearwardly while the feed rollers are inoperative.

15 31. An autographic register having a casing, a writing table therein, feed rollers for drawing apertured record strips across the table, an operating crank, a releasable stop member for intercepting the crank at the end of a cycle of operations, aligning pins adjacent the rear end of the writing table, means for rendering the feed rollers inoperative near the end of a cycle and for then projecting the pins upwardly to engage in the apertures and rearwardly to align and stretch the 30 strips across the table, and means operated upon release of the stop member to withdraw the pins from the paper apertures.

25 32. An autographic register including a casing adapted to contain a record strip having apertures therein, a table in the casing, feed rolls for feeding the record strip over said table, an operating handle for rotating the feed rolls, pins within the casing, means operatively associated with the operating 40 handle for moving the pins into engagement with the apertures in the record strip at a predetermined time, and means for moving the pins rearward to hold the record strip taut.

30 33. An autographic register including a casing adapted to contain a record strip having apertures therein, a table in the casing, feed rolls for feeding the record strip over said table, an operating handle for rotating the feed rolls, pins within the casing, means 45 operatively associated with the operating handle for moving the pins into engagement with the aperatures in the record strip at a predetermined time, and means operatively associated with the feed rolls for moving the pins 50 rearward to hold the record strip taut.

In testimony whereof, I affix my signature.
MAX SCHNEIDER.

CERTIFICATE OF CORRECTION.

Patent No. 1,814,637.

Granted July 14, 1931, to

MAX SCHNEIDER.

It is hereby certified that error appears in the printed specification of the above numbered patent requiring correction as follows: Page 9, after line 60, insert the following as claim 34:

34. In an autographic register, means for feeding a plurality of superimposed sheets of paper marked off into sections, means to engage one end of a section to align the sheets while the other end of the same section is in position to be engaged by the feeding means, and means for releasing the aligning means so connected to the feeding means that the feeding means can operate to feed the sheets only with the release of the aligning means.

and that the said Letters Patent should be read with this correction therein that the same may conform to the record of the case in the Patent Office.

Signed and sealed this 6th day of October, A. D. 1931.

(Seal)

M. J. Moore,
Acting Commissioner of Patents.
